W. M. MCKENZIE.
NUT TAPPING MACHINE.
APPLICATION FILED JULY 17, 1905.

UNITED STATES PATENT OFFICE.

WILLIAM M. MCKENZIE, OF WILKINSBURG, PENNSYLVANIA.

NUT-TAPPING MACHINE.

No. 823,225.

Specification of Letters Patent.

Patented June 12, 1906.

Application filed July 17, 1905. Serial No. 270,002.

To all whom it may concern:

Be it known that I, WILLIAM M. MCKENZIE, a citizen of the United States, residing at Wilkinsburg, in the county of Allegheny, State of Pennsylvania, have invented certain new and useful Improvements in Nut-Tapping Machines, of which the following is a specification, reference being had therein to the accompanying drawings.

10. This invention relates to a nut-tapping machine, and particularly to a structure adapted to effect an automatic feed and delivery of the nuts therefrom.

15. The invention has for an object to provide an improved construction and arrangement of the tap by which the same is supported and held by the nuts fed thereon after the tapping operation and delivered from the opposite end of the tap.

20. A further object of the invention is to provide an improved construction and arrangement of a pusher adapted to coöperate with said tap in its reciprocatory movement to permit the nut to be deposited in alignment 25 with the tap and there held during the threading operation.

25. A further object of the invention is to provide an improved arrangement of shaker in the feed-trough by which the nuts received from the hopper shall be presented to the tap in proper position to secure the most efficient results.

30. Other and further objects and advantages of the invention will be hereinafter set forth and the novel features thereof defined by the appended claims.

35. In the drawings, Figure 1 is a side elevation with parts in section; Fig. 2, an enlarged section of the tap and pusher mechanisms; 40 Fig. 3, an end view of the machine with the hopper and standard removed; Fig. 4, a plan of the shaker mechanism; Fig. 5, a vertical section through the holding-pawl; Fig. 6, a detail perspective of the chute for the nut-blanks, and Fig. 7 a detail plan of the holding-pawl and tapping-chamber with the pusher removed.

45. Like letters of reference refer to like parts in the several figures of the drawings.

50. The letter A designates the frame of the machine, which may be of any desired construction or configuration suitable for the purpose, and is provided with a vertical

standard A', adapted to support at its upper end a feed-hopper A', within which the nut-blanks to be tapped or threaded are contained. Upon this base A a head A³ is mounted and provided with a slideway within which a pusher B is disposed. This pusher is provided with a recess or opening 55 extending therethrough, as shown at B', to permit the discharge of chips from the threading operation, and is governed in its movement by the cam B¹, mounted upon a shaft B² in the head A³, this cam being adapted to engage with the lever B⁴, pivotally mounted in the head at B⁵ and provided at its lower portion with a hardened friction-roller B⁶, adapted to be supported in position by the threaded shank B⁷ thereof. 60 This roller is normally held in contact with the cam-surface by means of the tension-spring B⁸ extending between the lower end 65 of the lever and a fixed point. The upper end of the lever is provided with a rounded finger B¹⁰, seated in a suitable recess in the pusher, as shown clearly in Fig. 2. The travel of this lever is limited and adjusted by means of the screw b, mounted in the head 70 and adapted to engage a portion of the finger B¹⁰. This pusher at its forward end is adapted to travel beneath the chute or trough C, 75 through which the nuts descend, and to support the blanks therein while holding one of the blanks in position for the threading 80 operation. When the pusher is retracted, another blank is allowed to fall in position, where it is held in the tapping-chamber D by means of the oppositely-disposed pawls D', 85 each of which is provided with a point D², 90 against which the blank being threaded is held by the pusher. The subsequent movement of this pusher forces these pawls inward and allows the nut to travel upon the shank of the tap E after traveling over the 95 threaded end E' thereof. The pawls are held in position in any desired manner—for instance, by means of a spring D¹, bearing upon the head D⁵ of the pawl and held in position by a closing-screw D⁶, as shown in Fig. 5. 100 The tapping-chamber is also provided at its end face with a slot or way D⁷ to permit the discharge of material of chips collecting therein. The body of the pawl is preferably 105 angular in configuration and fits a similar recess in the walls of this chamber, so as to

keep the point D² thereof in proper position to engage the blank.

The chute or trough C is preferably formed open at the front, as shown at C', which permits a ready inspection of the blanks traveling therethrough and also prevents clogging by reason of the burs about the central apertures of these blanks. The rear wall of the trough is also provided with a recessed portion C' for the same purpose. The upper end of this trough is deflected into a plane obliquely to the vertical plane of the delivery end thereof and there provided with a shaker mechanism F for the purpose of introducing the blanks into the trough. This shaker is provided with an enlarged open portion at its upper end, into which the nuts are introduced by the feeder G from the hopper, and is also provided with a wall F² thereof, pivoted at its lower end F³ and provided with an arm F⁴, carrying a spring F⁵, connected to a fixed bracket F⁶, as shown in Fig. 4, which causes the movable wall to normally move toward the fixed wall. For the purpose of vibrating this movable wall a shaft F⁷ is mounted upon the upper face of the chamber and provided at its outer end with a driving-pulley F⁸, having upon the hub thereof a series of striker-pins F⁹, adapted to coöperate with a depending finger F¹⁰, carried by the arm F⁴, extending from the movable wall of the shaker. The result of this motion is to constantly vibrate the wall F², thus causing the blanks to be fed in a single series with their sides parallel to the wall and insures a feed thereof in proper position through the trough C.

The blanks may be fed directly into this shaker; but preferably the hopper is connected therewith by means of the rotatable feeding-cylinder G, provided interiorly with a spiral path or way, preferably formed of coiled wire, and at its upper end is provided with a roller-bearing G¹ within the lower end G² of the hopper, this bearing being secured in position by means of the threaded bearing G⁴, as shown by section in Fig. 1. The feeding-cylinder is rotated by means of a gear G⁵, mounted thereon and meshing with a coöperating gear G⁶, having its shaft journaled in a bracket A⁵, extending outward from the standard.

The parts hereinbefore described may be driven in any desired manner—for instance, by means of the driving-shaft II, provided at one end with a pulley II', belted at II² to a stepped cone H³, mounted upon a delivery-shaft I, which carries at its inner end the tap E. This driving-shaft II is also provided with a friction-wheel K, coöoperating with a similar wheel K', mounted upon a cross-shaft II' at the base of the machine, which shaft is provided with a driving-pulley II⁵, from which a belt II⁶ extends to a suitable driving-

pulley II⁷ upon the shaft of the cam B², before described. The opposite end of the shaft of this cam is also provided with a driving-pulley H⁸, from which a belt II⁹ extends to a pulley F⁸ upon the shaft of the shaker. This cam-shaft has at its opposite end a second driving-pulley J, from which a belt J' extends upward to the driving-pulley J², disposed upon the shaft of the gear G⁶ for rotating the feeder.

The tap E is provided intermediate of its opposite ends with portions E², deflected at opposite sides of a line extending between said ends, and this deflected portion of the tap, in connection with the completed nut traveling thereon, serves to hold the tap against any longitudinal thrust in either direction and also against slipping within the holder I' thereof, as the deflected or crank portion, with the nuts disposed thereon, (shown in Fig. 2,) serves to counteract any rotative motion of the shaft relative to this holder. This holder is threaded on the delivery-shaft I, as shown at I², and is preferably provided with a removable cap member I³, held in position by any desired means, such as the screws I⁴. (Shown in Fig. 1.) This cap portion can be conveniently removed whenever it is found necessary or desirable to change the tap and adjust another therein with the nuts thereon in proper position for holding it in action. The nuts in their longitudinal travel over the tap-shank are finally discharged at the end E³ thereof and are forced by contact with each other through the delivery-shaft I, mounted in suitable bearings I' and discharged from the open end I⁶, where they can be received in any suitable receptacle.

In the operation of this invention when it is desired to start the machine several nuts are disposed upon the shank within its holder, so as to retain the shank in position and the driving mechanism then started. The nuts are thus fed from the hopper or magazine through the tubular feeder and discharged into the shaker at the upper end of the chute. This shaker insures the passage of the nuts into the chute upon their flat sides, so as to fall on edge between the tap and the pusher, they being held in this position by the oppositely-disposed pawls in the tapping-chamber. The pusher in its movement then brings the nut-blank into contact with the tap and continues its pressure until the tap has passed through the nut and the latter passes from the threaded portion of the tap onto its shank. At this time the pusher lies beneath the nuts and the chute, thus supporting them in position, and the chips from the tapping operation pass through the aperture in the pusher. The tapping-chamber as well as the holder for the tap are provided with angular walls, so as to prevent

- rotation of the nut, and the subsequently-tapped nut forces the preceding one forward upon the tap-shank until it finally leaves the same and continues in its passage through 5 the hollow shaft of the tap-holder, from the end of which it is discharged, thus providing for a continued operation in the feed of the nut-blanks and the discharge of the tapped nuts. The construction of the tap-blank 10 with the crank portions at opposite sides provides means by which the tap is supported in its holder by the nuts traveling longitudinally thereon and also permits the ready removal and replacement of the tap for cutting any 15 desired size or pitch of thread in the nut-blank. The pusher in its movement forces the blank when tapped past the pawls, which are restored to their normal position by the springs, and at the termination of each tapping 20 movement the cam provides for a slight period of rest in order not to exert too great a strain upon the tap and to allow a space between the nuts, which are still traveling upon a threaded end of the tap. The driving 25 mechanism is constructed and arranged so that the speed of the tap may be varied by the stepped cone and the other parts driven therefrom also correspondingly varied in speed. The cam for driving the pusher may 30 be regulated in stroke by the adjustment of the friction-roll at its lower end and the travel of the pusher also determined by means of the adjusting-screw, adapted to contact with the finger carrying the pusher. 35 Having described my invention, what I claim, and desire to cover by Letters Patent, is—
1. In a nut-tapping machine, a threading tap having its shank deflected, a holder or 40 stock provided with a correspondingly-deflected passage inclosing the deflected portion of the shank and of greater diameter and disposed concentric to the longitudinal axis of the threading end of the tap, and means to 45 rotate said holder.
2. In a nut-tapping machine, a threading tap having its shank deflected, a holder or stock provided with a correspondingly-deflected 50 passage inclosing the deflected portion of the shank and of greater diameter and disposed concentric to the longitudinal axis of the threading end of the tap, means to rotate said holder, and means for intermittently feeding material to said tap. 55
3. In a nut-tapping machine, a tap having opposite end portions in the same plane and an intermediate curved deflected portion merging into said end portions, and a holder provided with a correspondingly-deflected 60 passage inclosing said deflected portion of the tap and of greater diameter and disposed concentric to the longitudinal axis of the threading end of the tap.
4. In a nut-tapping machine, a tap having 65 its shank provided with oppositely-deflected portions, and a tubular holder or stock provided with a correspondingly-deflected interior passage of greater diameter than the tap-shank and completely inclosing the deflected portion thereof. 70
5. In a nut-tapping machine, a tap having its shank provided with oppositely-deflected portions, a tubular holder provided with a corresponding interior passage of greater diameter than the tap-shank within which the 75 shank of the tap is disposed to permit the travel of nuts thereover, and a hollow delivery-shaft for said holder disposed adjacent to the free discharge end of said tap. 80
6. In a nut-tapping machine, a tap having its shank provided with oppositely-disposed crank portions intermediate of its ends, a holder for said shank having a passage of greater diameter than the shank to permit the travel of a nut upon the shank to effect a 85 driving connection between the tap and holder and a hollow delivery-shaft extended into the end of said holder with the passage therein in alignment with the passage of the holder. 90
7. In a nut-tapping machine, a tap having its shank provided with oppositely-disposed crank portions intermediate of its ends, and a holder for said crank portions provided with a co-operating interior channel of greater 95 diameter than said portions, and a removable cap-plate. 95
8. In a nut-tapping machine, a tap, a driving-pulley therefor, a head, a pusher mounted therein, a controlling-cam for said pusher 100 mounted in said head, a driving-shaft disposed parallel to the tap and geared to the shaft thereof, a laterally-disposed counter-shaft, a driving connection between the driving-shaft and counter-shaft, a belted connection 105 from said counter-shaft to the shaft of said cam, a shaker mechanism controlling a feed-chute, and a driving connection from the shaft of said cam to the shaker mechanism. 110
9. In a nut-tapping machine, a tap, a driving-pulley therefor, a head, a pusher mounted therein, a controlling-cam for said pusher 115 mounted in said head, a driving-shaft disposed parallel to the tap and geared to the shaft thereof, a laterally-disposed counter-shaft, a driving connection between the driving-shaft and counter-shaft, a belted connection from said counter-shaft to the shaft of 120 said cam, a shaker mechanism controlling a feed-chute, a driving connection from the shaft of said cam to said shaker mechanism, a hopper and feeding means therefrom, and a driving connection from said cam-shaft to said feeding means. 125
10. In a nut-tapping machine, a tap provided with an extended deflected shank, a holder for said shank provided with an interior passage of greater diameter than the

shank and corresponding to the configuration of the shank to retain the shank against relative rotary or longitudinal motion by means of the completed article passing over the said shank, and a hollow delivery-shaft connected to said holder and having the free discharge end of said shank disposed therein.

In testimony whereof I affix my signature in presence of two witnesses.

WILLIAM M. MCKENZIE.
